(57) **CLAIM**

The ornamental design for a food container, as shown and described.

DESCRIPTION

FIG. 1 is a top, front perspective view of a food container showing my new design.

FIG. 2 is a top plan view thereof.

FIG. 3 is a front view thereof.

FIG. 4 is a rear view thereof.

FIG. 5 is a left side view thereof;

FIG. 6 is a right side view thereof; and,

FIG. 7 is a bottom plan view thereof.

The broken lines represent portions of the food container that form no part of the claim.
